US0D1039867S

(12) **United States Design Patent** (10) **Patent No.:** **US D1,039,867 S**
(45) **Date of Patent:** **** Aug. 27, 2024**

(54) **AUTO DISPENSER**

(71) Applicant: **Chundan Liao**, Guangdong (CN)

(72) Inventor: **Chundan Liao**, Guangdong (CN)

(**) Term: **15 Years**

(21) Appl. No.: **29/943,749**

(22) Filed: **May 23, 2024**

(30) **Foreign Application Priority Data**

Mar. 5, 2024 (CN) 202430110957.6

(51) **LOC (14) Cl.** **23-08**

(52) **U.S. Cl.**

USPC **D6/542**

Primary Examiner — Nathan M Johnston

(57) **CLAIM**

The ornamental design for an auto dispenser, as shown and described.

DESCRIPTION

FIG. 1 is a front, right and top perspective view of an auto dispenser, showing my new design.

FIG. 2 is a rear, left and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the drawings are for the purpose of illustrating portions of the auto dispenser that form no part of the claimed design.

1 Claim, 8 Drawing Sheets
